Des. 211,351
Patented June 11, 1968

211,351

ELECTRICAL INSULATOR OR SIMILAR ARTICLE

William Austin Lankford and William H. Gilliland, Birmingham, Ala., assignors to USCO Power Equipment Corporation, Birmingham, Ala., a corporation of Alabama

Filed May 9, 1966, Ser. No. 2,225

Term of patent 14 years

(Cl. D26—10)

Fig. 1

Fig. 2

FIGURE 1 is a side elevational view of one embodiment of an electrical insulator or similar article, showing our new design, the opposite side being substantially a mirror image thereof.

FIGURE 2 is a vertical sectional view through the center of one of the skirts of FIGURE 1.

FIGURE 3 is a side elevational view of a second embodiment of an electrical insulator or similar article showing our new design, the opposite side being substantially a mirror image thereof.

FIGURE 4 is a vertical sectional view through the center of one of the skirts of FIGURE 3.

FIGURES 5 and 6 are top and bottom views of the embodiments of the electrical insulator or similar article shown in FIGURES 1 and 3 the top view and bottom view of each embodiment being similar.

We claim:

The ornamental design for an electrical insulator or similar article, as shown and described.
